UNITED STATES PATENT OFFICE.

SILAS W. WILLIAMS, OF GORDO, ALABAMA.

CLEVIS-PROTECTOR.

1,213,720.

Specification of Letters Patent. Patented Jan. 23, 1917.

Application filed September 15, 1916. Serial No. 120,370.

To all whom it may concern:

Be it known that I, SILAS W. WILLIAMS, a citizen of the United States, residing at Gordo, in the county of Pickens and State 5 of Alabama, have invented new and useful Improvements in Clevis-Protectors, of which the following is a specification.

This invention relates to clevis protectors.

The object of the invention is to provide a 10 removable and reversible means to be applied to a clevis, to prevent wear from the lap link.

With the above and other objects in view the invention consists of a cylindrical body 15 provided with a pair of oppositely located, substantially semi-circular channel shaped members formed upon one end of the said body, the said semi-circular members to be applied to that portion of a clevis subject to 20 wear from the lap link.

In the drawings, Figure 1 is a perspective view of a clevis having the improved protector applied thereto. Fig. 2 is a detailed longitudinal section showing the manner 25 of fitting the body portion of the protector upon the clevis. Fig. 3 is a detailed sectional view illustrating the manner in which the protector hugs that portion of the clevis subject to wear. Fig. 4 is a detailed 30 perspective view of the protector.

It has been found by practice that the ordinary clevis used on a plow quickly becomes worn and consequently broken owing to the wear upon the same, caused by the 35 rubbing of the lap link. The life of the clevis is therefore very short, and it is to prolong its use that the present invention has been provided.

The invention as shown consists of a cylindrical body member 1 adapted to be slipped 40

over the projection 2 formed on that portion of the clevis which extends into the plow 3. The body member 1 has formed integrally therewith a pair of oppositely located semi-circular members 3. These 45 members are channel shaped in cross section, and as shown in the drawings are adapted to securely fit within the grooved portions of the clevis, against which the lap link usually rubs. As before stated the rubbing of 50 the lap link quickly causes the clevis to wear at this point, and therefore become useless. The semi-circular portions of the protector are therefore adapted to take up the wear occasioned by this link. By reason of the 55 protector being provided with a pair of these semi-circular members 3, it will be apparent that it may be readily reversed so as to prolong its use.

From the foregoing it will be apparent 60 that the invention provides a cheap and easily adjusted protector, to take up the wear of a clevis occasioned by the lap link, the said protector being reversible in order that its use may be prolonged. 65

Having described the invention what I desire to claim and secure by Letters Patent, is:

1. The combination with a clevis of a protector comprising a cylindrical body, a pair 70 of oppositely located substantially semi-circular channel shaped members formed upon one end of said body.

2. The combination with a clevis, of a protector shaped to snugly fit the inner vertical 75 portion of the front end of the clevis and means for removably securing the protector thereto.

In testimony whereof I affix my signature.
SILAS W. WILLIAMS.
